UNITED STATES PATENT OFFICE.

WILLIAM JAY FULLER, OF LEEF, WISCONSIN.

HAND-POWER STUMP-PULLER.

No. 821,479.

Specification of Letters Patent.

Patented May 22, 1906.

Application filed September 21, 1905. Serial No. 279,566.

To all whom it may concern:

Be it known that I, WILLIAM JAY FULLER, a citizen of the United States, residing at Leef, in the county of Burnett and State of Wisconsin, have invented certain new and useful Improvements in Hand-Power Stump-Pullers, of which the following is a specification.

This invention relates to stump-pullers, particularly those adapted to be operated by hand, and has for its particular object to provide a device of this character by which an enormous pulling strain can be exerted upon the stump or other object to be displaced with relatively little effort upon the part of the operator.

A further object of the invention is to provide a simple, durable, and reliable stump-puller which can be manufactured at small cost and which can be packed into small compass when not in use.

With these and other objects in view the present invention consists in the combination and arrangement of parts, as will be hereinafter more fully described, shown in the accompanying drawings, and particularly pointed out in the appended claims, is being understood that changes in the form, proportion, size, and minor details may be made within the scope of the claims without departing from the spirit or sacrificing any of the advantages of the invention.

In the drawings, Figure 1 is a perspective view of my improved construction. Fig. 2 is a detail view, partly in section, showing the construction of the ends of the chain-grappling members; and Fig. 3 is a detail perspective view of one end of the operating-lever and attachments.

Like characters of reference designate corresponding parts throughout the several views.

In the drawings, 1 designates a lever having a handle portion 2 and a slotted or yoke portion 3 at the opposite end thereof.

Secured within the slot 4 of the lever 1 are pivotally-mounted grappling members or arms 5, the said members being secured by bolts 6, passing through openings 6'. The arms 5 are provided with curved or bent extensions 7, having an opening 8 therethrough. The opening 8 is approximately pear-shaped with the end or narrow portion adjacent the extremity of the arm. The extensions 7 with the pear-shaped openings therein constitute grappling-yokes which are adapted to

engage a chain 9 or equivalent rope or cable for the purpose hereinafter more fully set forth. The ends of the arms 5 opposite the grappling-yoke are united by a spring 10, secured within openings 11 and tending to separate the yoke members. One of the arms 5 is somewhat shorter than the other, so that each may engage different portions of the same chain and not interfere with the operation of the other member.

Secured to the slotted portion 3 of the lever 1 approximately midway between the bolts 6 is a guide ring or loop 12, through which the chain 9 passes. To this ring or loop 12 is secured a guide-rod 13, fastened thereto by a bolt 14 or other suitable means. The guide-arm 13 passes through guide-yokes 15, secured to the curved or bent extension 7 of the arms 5. Pivotedly secured to the lever 1 between bolts 6 is a U-shaped band carrying a hook 16. This band is preferably secured to the lever 1 by the bolt 17. The chain 9, which is engaged within openings 8 and the guiding ring or loop 12, passes around the sheave 18 of the pulley 19 and back into proximity to the lever 1, where it is secured to the hook 16. The sheave is provided with a slot or groove 20, designed to prevent twisting of the chain as it is drawn through the pulley 19. A chain 21 or other cable or like means is connected to the hook 22, which is pivoted in the block of the pulley 18.

The operation of my improved stump-puller is as follows: The chain or cable 21 is first secured to the stump to be pulled, and its other end is connected to the pivoted hook 22. The chain 9 is then drawn tight and anchored to some rigid object in any well-known manner. The operating-lever 1 is then moved backward and forward, and the grappling-yokes 8 are alternately moved along the chain 9, the yoke of one arm engaging a link of the chain while pressure is brought to bear upon the stump by the movement of the lever 1, and the other grappling-yoke is advanced along the chain 9. A movement of the lever 1 in the opposite direction repeats the operation. The handle 2 is moved backward and forward, as described, until the stump is uprooted and displaced.

Having thus described my invention, what I claim as novel, and desire to secure by Letters Patent, is—

1. In a device of the character described, a chain adapted to be anchored, pulling means connected thereto, said means comprising an

operating-lever, a plurality of arms pivoted thereto, grappling-yokes carried by said arms at one end thereof, elastic means tending to move the said grappling-yokes apart and means adapted to connect the said pulling means with a stump to be uprooted.

2. In a device of the character described, a chain adapted to be anchored, pulling means connected thereto, said means comprising an operating-lever, a chain-guide carried thereby and surrounding the said chain, a plurality of arms pivoted to the said lever, grappling-yokes carried thereby, said yokes surrounding the said chain and adapted to engage therewith, a guide-rod carried by the operating-lever, guide-yokes secured to the grappling-yokes and in engagement with the said guide-rod, and means adapted to connect the pulling means with a stump to be uprooted.

3. In a device of the character described, a chain adapted to be anchored, pulling means

connected therewith, said means comprising an operating-lever, a chain-guide carried thereby and surrounding the said chain, a 25 plurality of arms pivoted to the said lever, grappling members carried by the said arms and adapted to engage the said chain, a guide-rod carried by the operating-lever, 30 guide-yokes secured to the grappling members and in engagement with the said guide-rods, a pulley about which the said chain passes, a hook carried by the pulling means to which one end of the said chain is attached, means adapted to connect the said pulley 35 with a stump to be uprooted, and a pivoted hook interposed between the pulley and the said last-named means.

In testimony whereof I affix my signature in presence of two witnesses.

WILLIAM JAY FULLER.
